US0D1010028S

(12) **United States Design Patent** (10) **Patent No.:** **US D1,010,028 S**
(45) **Date of Patent:** ** *Jan. 2, 2024

(54) **UNWEIGHTING EXERCISE TREADMILL**

(71) Applicant: **Boost Treadmills, LLC**, Palo Alto, CA (US)

(72) Inventors: **Sean Whalen**, Mountain View, CA (US); **Thomas Allen**, Palo Alto, CA (US); **Robert Tremaine Whalen**, Los Altos, CA (US)

(73) Assignee: **Boost Treadmills, LLC**, Palo Alto, CA (US)

(*) Notice: This patent is subject to a terminal disclaimer.

(**) Term: **15 Years**

(21) Appl. No.: **29/643,045**

(22) Filed: **Apr. 4, 2018**

(51) LOC (14) Cl. **21-02**

(52) U.S. Cl. **D21/669**
USPC .....

(57) **CLAIM**

The ornamental design for an unweighting exercise treadmill, as shown and described.

DESCRIPTION

FIG. 1 is an isometric rear, top view of the unweighting exercise treadmill showing our new design;

FIG. 2 is in isometric front, bottom view thereof;

FIG. 3 is a rear view thereof;

FIG. 4 is a front view thereof;

FIG. 5 is a left side view thereof;

FIG. 6 is a right side view thereof;

FIG. 7 is a top view thereof; and,

FIG. 8 is a bottom view thereof.

The broken lines shown in the figures depict portions of the unweighting exercise treadmill that form no part of the claimed design.

1 Claim, 8 Drawing Sheets
